UNITED STATES PATENT OFFICE.

WILLIAM BANKS, OF MONTGOMERY COUNTY, MICHIGAN.

DESIGN FOR A TOMBSTONE.

45,143.

Specification for Design.

Patented Jan. 13, 1914.

Application filed October 25, 1913. Serial No. 797,353. Term of patent 14 years.

To all whom it may concern:

Be it known that I, WILLIAM BANKS, a citizen of the United States, residing in the county of Montcalm and State of Michigan, have invented a new, original, and ornamental Design for Tombstones, of which the following is a specification, reference being had to the accompanying drawing, forming part thereof.

The figure is a perspective view of a tombstone, showing my new design.

I claim:

The ornamental design for a tombstone, as shown.

WILLIAM BANKS.

Witnesses:

CHAS. W. WITHEY,
HIRAM B. HAIGHT.
